UNITED STATES PATENT OFFICE.

THOMAS S. KEMBLE, OF LAKewood, OHIO.

MUFFLER CONSTRUCTION.

Application filed April 3, 1922. Serial No. 549,010.

The present invention relates to a muffler for use with internal combustion engines, or under any circumstances where a pulsating gaseous stream is discharged into the atmosphere, as for instance, the smoke pipe of a locomotive or the exhaust pipe of a steam engine.

The muffler of the present invention is similar in some respects to the muffler disclosed in my Patent No. 1,357,992, and in my application for patent Serial No. 514,566, filed Nov. 12, 1921.

In certain features of construction, however, and in certain features of operation, it differs from both of the preceding.

The object of the invention is to provide a muffler which is particularly intended for use under circumstances where it is desired to eliminate as much of the noise in connection with the exhaust of an internal combustion engine as is possible, and without creating an undue back pressure. It has the further advantage that a tail pipe may be used in connection with it, to carry the exhaust gases to a point remote from the muffler.

Reference should be had to the accompanying drawings forming a part of this specification, in which Fig. 1 is a sectional elevation of a muffler embodying my invention; Fig. 2 is a top plan view; Fig. 3 is an end elevation; Fig. 4 is a section on the line 4—4 of Fig. 1; Fig. 5 is a sectional elevation of a modified form; Fig. 6 is a part section and part elevation of a modified construction; Fig. 7 is a section of a portion of the device shown in Fig. 5.

Reference should be had to the accompanying drawings which show several different forms or devices in which the present invention may be embodied, and of all these various forms it may be said that they provide a direct passage for the pulsating gaseous stream, and a chamber or enlarged secondary passage which is connected by suitable openings with the main passage so that gas may pass out of the direct stream into the chamber, thereby relieving the pressure incident to the puffs of the gaseous matter in the main stream, and this gas which passes into the enlarged chamber is drawn back again into the main stream through the opening or openings which establish communication between the direct passage and the chamber.

In Fig. 1 a construction is shown wherein

there is a conduit 1 providing a direct passageway for the travel of the gas and a chambered member 2 at one side of the direct passageway, and this chambered portion 6⁶ communicates with the main passageway by means of openings 3 and 4 which are arranged adjacent the opposite ends of the chambered portion 2. It is not intended to limit the invention to the precise form of 65 the chambered member and the direct passageway as shown, but for a fuller explanation it may be said that the central portion of the device may be considered a cylindrical shell like member 5 at the ends of which 70 are similar members which assume the form of oblique cones, as indicated at 6.

The direct passageway 1 may be formed by providing a cylindrical member or partly cylindrical member 7 which co-operates with 75 the lower rounding surface of the cylindrical portion 5 and oblique conical portion 6 thereby forming a substantially tubular passageway 1. The member 7 will be cut out to provide openings, as indicated at 3 and 4. 80

In using this device one end of the same will be connected to the exhaust manifold of an engine or any other device from which there is emitted a pulsating gaseous stream, and the opposite end of the device here described may be attached to a tail pipe for conducting the gaseous products so as to discharge them at any given point, or such a pipe may be omitted. 85

When a pulsating gaseous stream enters 90 at one end of the tubular portion 7, it may enter the direct passageway 1, but portions of this gaseous stream will enter into the chambered portion 2 through the opening 3 or 4, as the case may be, and thus relieve the 95 pressure of the puffs which are passing through the device, and this same gas which passes into the chamber 2 will at some time thereafter again enter the main stream line of the gas through either of the openings 3 100 or 4, as the case may be.

Referring to Fig. 5, which is a modified form, 10 is an elongated tube which as shown is slightly tapered, but the invention is not limited to a tapered form, as a tube of constant diameter may be used with approximately the same results as when using a tapered tube. This tube is provided with a large number of openings which openings extend substantially from one end of the 110 tube to the other.

These openings may be of any desired

form, that is, they may be slot-like or round, or they may be formed as suggested in Fig. 5 and more clearly shown in Fig. 7, by making a cut in the metal and elevating one of the edges of the cut such as indicated at 11 in Fig. 7.

Surrounding the tube 10 is a casing 12 which in the present instance is shown as tapering, but it should be noted that the casing is not necessarily tapering, as will be later explained in connection with Fig. 6. This casing is secured to the tube 10 adjacent the outer end thereof, as indicated at 12^a, and is also secured to the inner end of the tube as indicated at 11^b.

The inner end of the tube 11 is of suitable size and shape to engage with the end of the exhaust manifold of an engine which is indicated at 13.

20 If desired braces such as indicated at 14 may be provided within the casing 12.

In Fig. 6 there is shown an inner tube 15 which as appears in the drawing is slightly tapering, but as remarked with respect to 25 the showing in Fig. 5, this tube is not necessarily limited to a tapering form. The tube is provided with a plurality of openings, such as indicated at 16, and these openings may be round holes as indicated, or they may 30 be made of tapering form which is shown in Figs. 5 and 7. These openings extend substantially throughout the length of the tube 15.

Surrounding the tube 15 is a casing 17. 35 This casing is substantially a cylindrical casing, except that the ends where it is caused to slant as indicated at 17^a, 17^b. This is for the purpose of securing the casing 17 to the opposite ends of the tube 15.

40 It will be noted in the construction shown in Figs. 1, 5 and 6, the surrounding casings indicated at 5, 12 and 17 are imperforate, and are closed at their end portions, thereby providing a chamber surrounding the central tubular member, which casing is air tight.

The tubes forming direct passageways, such as represented at 7, 10 and 15, are open from end to end, and free from obstruction.

50 The gases in passing through such tubes as shown at 14 and 15, pass in a series of impulses, and as the gas is passing through the tubes it may find exit through these various 55 openings scattered throughout the inner tube, relieving the pressure of the exhaust gases through the inner tube, these gases expanding into the chambered portion surrounding each inner tube, and thereby serving to diminish the pressure, and consequently 60 the noise incident to the exhaust of the gases. As before stated, this chambered por-

tion surrounding an inner tube is closed, and while the gas may expand into this chambered portion upon an impulse of the exhaust gas it will not remain in the chambered portion, because following each impulse is a relief of pressure, or what may be termed a suction, so that the gas which passes into the chambered portion finds its way to the tubular member 6, although it may well be 70 that the gas that enters into the chambered portions through one or more of the openings does not return to the tubular member through the same opening.

In all of the forms of the device described, 75 the net effect of passing exhaust gases through the direct passageway with its surrounding chamber, is to materially reduce the noise which would otherwise be incident to the exhaust of the gases against the atmospheric pressure.

80 Due to the fact that the inner tube is entirely open and unobstructed the back pressure which is incident to the use of the device described is so small as to be practically negligible.

Having described my invention, I claim:

A muffler adapted to form the discharge section of an engine exhaust conduit and having an elongated imperforate tubular 90 outer casing of greater diameter than the exhaust conduit and having a conical end with an opening adapted to receive the exhaust conduit, the opposite end of said casing being conical and having an opening 95 through which the gases are discharged, a tubular member within said casing in alignment with the exhaust conduit and extending from one conical end portion of the casing to the other, said tubular member being of substantially the same size at its inlet end as the exhaust conduit and forming a direct and unobstructed passageway for gases discharged from the exhaust conduit, the space 100 between said tubular member and outer casing being in communication with the direct passageway adjacent the inlet and outlet ends of the muffler and forming an elongated unobstructed auxiliary passageway 105 from the inlet to the outlet end of the muffler, the said passageways being of such length and relative cross-sectional areas that substantial portions of each discharge of exhaust gases may escape laterally to the auxiliary passageway at the inlet end, flow 110 through the same toward the discharge end of the muffler and return into the direct passageway at the discharge end of the muffler. 115

In testimony whereof, I hereunto affix my signature.

THOMAS S. KEMBLE.
